CYLINDRICAL DIE CONSTRUCTION AND DIE
ASSEMBLY

Claude C. Hall, Portland, Oreg.

Application November 30, 1936, Serial No. 113,367

5 Claims. (Cl. 107—8)

This invention relates to dies adapted to the manufacture of compressed animal feeds, and it particularly relates to cylindrical shaped dies used in connection with molding apparatus of the type in which a conglomerate mass is acted upon by rollers and forced through a foraminous cylindrical die.

Actual tests have definitely proved that the resistance offered by a die to the passage of a conglomerate mass as it is continually forced through the perforations in the die creates a considerable amount of frictional heat with a consequent expansion of the foraminated die. It has also been found that the die supporting and retaining member and the die retaining and reinforcing collar also become heated through conduction, but do not expand as rapidly or as much as the die. Unless provision is made for this expansion of the die, it is forced to operate under strain. Furthermore, experience has shown that, when a die which has operated under the foregoing conditions, is permitted to cool off, it becomes smaller in diameter. Consequently, when the same die is sought to be used, it will not, without some changes being made, fit properly into its seat on the die supporting and retaining member. And oftentimes, when a die which has gone through the experience above related, it will break when used a second time, because the die itself cannot withstand the pressure to which it is subjected unless it is reinforced by the two retaining members.

To overcome and avoid these inherent disadvantages, provision is made by my invention whereby the die supporting and retaining member and the die retaining and reinforcing collar may be loosened or tightened around the die and thus provide at all times a proper working condition for the die. Furthermore, provision is also made, by dividing the die into two semi-circular sections, for a nominal amount of expansion of the die; and, if necessary, during the operation of the apparatus, the die supporting and retaining member and the die retaining and reinforcing collar may be loosened to afford greater expansion.

An additional feature of the invention may be found in the ease with which a die may be replaced without the necessity of dismantling any portion of the apparatus, and also it is possible to remove but one semi-circular section, if for any reason it is desired to do so, and replace it with another.

My present invention is closely related to a feed forming machine of the type illustrated, de-

scribed and claimed in my United States application for an improvement in "Feed forming machines", Serial No. 88,766. The essential difference between the die construction and die assembly disclosed in the pending application and the present invention herein set forth is in the provision of means whereby the die may expand or contract without fear of any deleterious results and which permit and facilitate the removal of the die from the apparatus.

While, as pointed out, this invention is closely related to my pending application, the invention may be incorporated and used with other feed forming machines with equal advantage, since all the invention contemplates is to provide the changes heretofore referred to which will overcome the disadvantages pointed out in the foregoing.

The quintessence of this invention is to provide means whereby the die may expand or contract without fear of being rendered useless.

Another object of the invention is to provide a die supporting and retaining member which is adapted to be tightened or loosened around the base of the die.

Still another object of the invention is to provide a die retaining and reinforcing collar which is adapted to be tightened or loosened around the top of the die.

An equally important object of the invention is to provide a tapered foraminated die composed of two semi-circular sections.

A further object of the invention is to provide means for raising or lowering the die in order to attain the desired relation between the die and the remainder of the apparatus.

Another object of my invention is to provide a die which may be easily secured to or removed from the rest of the apparatus with which it is used.

The primary object of my invention is to provide a die which permits an even distribution of the conglomerate mass being processed on the inner face of the die so that the resulting compressed material which is extruded through the openings of the die possess substantially uniform density.

Another object of the invention is to provide a die which is durable in construction and adapted for use for a relatively long period of time without fear of uneven wear or deterioration and which may be replaced when the deterioration sets in without the loss of time and with little effort.

The invention is directed to other objects and

possesses other features of novelty and advantage, all of which will become readily apparent from the following detailed description which must be read in conjunction with the accompanying drawing which illustrates but one embodiment by which the invention may be realized and in which:

Figure 1 is an elevational view, partially in section and partially broken away, of a cylindrical die and die assembly embodying the principles of my invention;

Figure 2 is a top view, partially broken away, taken on line 2—2 of Figure 1, looking in the direction indicated, showing the constructional details of the apparatus embodying the principles of my invention;

Figure 3 is an elevational view of one of the cylindrical die sections embodying the principles of my invention; and

Figure 4 is an end view, taken on line 4—4 of Figure 1, looking in the direction indicated, showing the manually operated means for raising or lowering the die.

Like reference characters are employed to designate identical parts throughout the several views of the drawing.

In Figure 1 is shown a fragment of a frame 1 possessing a conventional design, the details of construction of which need not be shown or described, because it does not apply directly to this invention. A portion of a shaft 2 is also shown as well as a pair of roller supporting members 3 and 4 and a plurality of tapered rollers 5. All of the foregoing members and elements are merely illustrative of a feed forming apparatus to which my invention may be applied, but the principles of which may be applied to other feed forming apparatus.

A main supporting block 6 is rotatably disposed about shaft 2 as its axis. An annular ledge 7 extends upwardly from this block 6, and the top surface of this ledge 7 has a plurality of inclined cams 8 formed therein.

A split annular die supporting and retaining member 9 has an equal number of inclined cams 10 incorporated within its base. These cams are identical in area and complementary in inclination to cams 8. It may be graphically seen in Figures 1 and 4 that, when the base of the die supporting and retaining member is placed upon ledge 7, cams 8 and 10 are positioned in intimate complementary relation.

A stop lug 11 extends from the side of the die supporting and retaining member 9; and a lug 12, having a threaded opening therein, extends from the side of ledge 7. These lugs are in registerable alignment with each other. An adjustment screw member 13 is disposed within the opening in lug 12 and the head 14 of the adjustment screw contacts at all times the stop lug 11. By this arrangement, it becomes apparent that, as the adjustment screw 13 is turned so that the head is moved away from lug 12, the die supporting and retaining member 9 is forced to ride upon the inclined complementary planes formed by cams 8 and 10. As a result of this action, the die supporting and retaining member 9 is raised or lowered in proportion to the distance the two lugs 11 and 12 are kept apart by adjustment screw 13.

A pair of lugs 15 and 16 extend from the side of the die supporting and retaining member 9 and each has an opening that is in registerable alignment with each other. A bolt 17 passes through these openings and nut 18 is threaded

upon the bolt. The function of this structure will be pointed out shortly.

An annular die seat 19 is formed within the top of the die supporting and retaining member 9, and the remainder of the top which surrounds 5 this seat is inclined downwardly, as shown at 20, at right angles to the working surface of the die which has yet to be described. This provision is necessary and desirable because the thickness of the working surface of the die may be varied; 10 and when the thickness of the die is greater than shown in the drawing, the added thickness of the die extends over the inclined surface 20.

The die, generally designated by reference character A, is composed of two semi-circular 15 segments 21 and 22. The position of these two segments with respect to each other may best be seen in Figure 2. For an illustration of the structural details of each of the segments, reference should be made to Figure 3. The description of 20 this segment, which, for convenience, will be numbered 21, should suffice for both segments 21 and 22, since they each possess identical features and contours.

Segment 21 has ends 23 and 24 which register 25 with like ends on segment 22, when the two segments are positioned in working relation. Each segment also has a semi-circular integral ledge 25 formed at its base 26. The main or working portion 27 of each segment tapers outwardly and has a plurality of passages or openings 28 disposed therethrough at right angles to the inner and outer faces of the working portion 27.

Although these passages are shown in the drawing to be circular in shape, it is obvious that 35 the size, shape and position of the passages may be varied to suit the needs of manufacturing feeds of different shapes.

A shoulder 29 is formed adjacent the top 30 of each segment, the value of which will be pointed 40 out shortly.

It is advisable at this time to point out that the ledge 25 of each die segment is formed so that it sits upon seat 19 formed in the die supporting and retaining member 9, when the two segments 45 21 and 22 are placed in working relation to each other. It is possible then to tighten the die supporting and retaining member around the ledge 25 by the conventional manipulation of the bolt 17 and nut 18. This arrangement insures not 50 50 a proper seat for the two segments, but retains them in working relation.

Consideration must now be given to the split retaining and reinforcing collar 31. This collar has an annular seat 32 formed therein in order 55 to permit the collar to engage a portion of the top 30 of each segment; also to engage the shoulder 29 of each segment. Lugs 33 and 34 extend from the side of the die retaining and reinforcing collar 31 and each has an opening which 60 is registerably aligned. A bolt 35 passes through the openings and a nut 36 is threaded upon the bolt in the conventional manner. By this arrangement, not only are the two segments 21 and 22 held together, but the top of each of 65 the die segments is reinforced.

From the foregoing description, it will undoubtedly appear that the invention as described satisfies the objects and points out the advantages claimed for this invention. While the invention has been described in connection with a specific embodiment, it should be understood that variants thereof are possible to those skilled in the art. The invention, therefore, in its broader aspect, is not limited to the specific construction 70 75 75

herein shown and described, since changes and alterations may be made in the proportions and arrangements of the various parts without departing from the spirit of the invention.

5 Having thus described my invention what I claim as new and upon which I desire to secure Letters Patent is:

10 1. The combination with a feed forming machine of the type having a plurality of rollers, of a foraminated cylindrical die surrounding said rollers, said die consisting of two semi-circular segments, the faces of which are tapered, means for supporting and retaining said die segments in working relation to each other, means for retaining and reinforcing the top portions of said die segments and means for simultaneously raising or lowering said die segments when desired.

15 2. A device characterized as in claim 1 wherein the means for supporting and retaining said die segments consists of a split annular member having an annular seat therein, and lugs registerably aligned adapted to be joined to effect a tight connection between the die segments and said annular member.

20 25 3. A device characterized as in claim 1 wherein the means for retaining and reinforcing the top portions of said die segments consists of a split annular collar having an annular seat therein, and lugs registerably aligned adapted to be joined to effect a tight connection between the top portions of said die segments and said annular collar.

30 4. In a feed forming machine, a main support-

ing block, said block having a multi-cammed annular ledge extending upwardly therefrom, a split annular die supporting and retaining member having a multi-cammed base, positioned upon the ledge of said block so that the respective cams are in complementary inclined relation with each other, a tapered foraminated cylindrical die composed of two semi-circular segments positioned upon and secured by said supporting and retaining member, means secured to said supporting 10 block and said supporting and retaining member for raising or lowering said die, and a split retaining and reinforcing collar positioned upon the top portion of said die.

15 5. A foraminated cylindrical tapered die comprising two semi-circular segments, each segment having a ledge extending from its base and a shoulder formed adjacent its top, a split annular die supporting and retaining member having an annular seat therein, the ledge of each die segment adapted to sit upon said seat, means incorporated within said die supporting and retaining member for effecting a tight connection between the two die segments and said member, a split 20 annular retaining and reinforcing collar having 25 an annular seat therein, said collar adapted to be seated upon the top portion of said die segments so that it covers the shoulder of each die segment and means for tightening said collar around said shoulder to thereby retain said die segments 30 together.
